UNITED STATES PATENT OFFICE

DEWITT TAPPAN, OF ROCHESTER, NEW YORK, ASSIGNOR, BY MESNE ASSIGNMENTS, TO NORTH EAST APPLIANCE CORPORATION, OF ROCHESTER, NEW YORK, A CORPORATION OF NEW YORK

ODOMETER

Application filed January 12, 1928. Serial No. 246,344.

This invention relates to odometers of the type in which a series of number rings are mounted to revolve upon a drum, and are interconnected by transfer pinions located within the number rings and partially within the periphery of the drum.

The object of the invention is to improve the construction of odometers of the type in question, particularly with respect to the construction of the drum on which the number rings revolve, in such a manner as to simplify and cheaper the construction and facilitate the assembling of the odometer.

To the foregoing end the invention resides in an odometer in which the drum consists of a generally cylindrical tubular sheet-metal member, associated with heads of suitable form, and in which other novel and useful features of construction are embodied, as hereinafter set forth.

In the accompanying drawings, Fig. 1 is a fragmentary longitudinal view, chiefly in section, of an odometer embodying the present invention. Fig. 2 is an end elevation of one of the heads of the drum; Fig. 3 is an end elevation of the driving gear; Fig. 4 is an end elevation of the first or driven number ring; and Fig. 5 is a perspective view of the body of the drum.

The invention is illustrated as embodied in an odometer in which the body 6 of the drum consists of a piece of suitable sheet metal, curved into the general form of a cylinder, but with a wide slot in one side, as shown in Fig. 5. Associated with this sheet metal body are two heads 7 and 8, which are preferably made by a die-casting operation. Each head is provided with a slot 9, of suitable form to receive one end of the body 6, a flange 10 lying just within the slot 9, a central opening 11 to receive a tie rod, and an off-center opening 12 to receive one end of the pinion shaft. In the case of the head 7, the opening 12 is surrounded by an inwardly projecting boss 13.

Any required number of number rings 14 may be mounted upon the drum, and these rings, with the exception of the first or driven ring, are of ordinary form and are interconnected by transfer pinions 15, also of ordinary

form. The pinions turn upon a pinion shaft 26, mounted in the appropriate openings in the heads. Preferably, the pinion shaft is made a tight or press fit in the boss 13 of the head 7, and is arranged to project slightly outside the head, as shown in Fig. 1. The pinion shaft may be fitted loosely in the head 8, to facilitate assembling the odometer.

The drum and number-ring assembly is adapted to be mounted upon and between members 16 and 17 of the frame of the instrument. This frame is not further illustrated, as it may be of any ordinary or suitable form. For the purpose of securing the odometer assembly in the frame, and for the further purpose of holding the several members of the drum in suitable relation, a tie rod 18 is used, which passes centrally through the drum and is provided, at its right-hand end, with an enlarged head 19 of cylindrical form. The left-hand end of the tie rod is threaded, as shown in Fig. 1, into an opening in the frame member 16. The head 19 fits loosely in an opening in the frame member 17. When this tie rod is screwed home, the head of the tie rod presses against the head 8 of the drum, and thus clamps the drum members tightly against each other and against the frame member 16. The projecting end of the pinion shaft 26 seats in a suitable recess in the frame member 16, and thus serves to prevent any rotative movement of the drum with respect to the frame.

In addition to its functions of securing the drum members together and of supporting the odometer in the frame, the tie rod provides a bearing for a drive gear through which the odometer is actuated. This gear 22 turns upon the head 19 of the tie rod, between the frame member 17 and the drum head 8. The first or driven number ring 20 is provided with two driving recesses 21, as shown in Fig. 4, the recessed portion overhanging the periphery of the head 8, and the drive gear 22 is provided with corresponding projections 23, which enter the recesses 21. The gear is driven by any ordinary or suitable means, and it turns the ring 20 directly and positively, the movement being transferred to the succeeding number rings 100.

through the transfer pinions in the usual manner.

It will be evident that the entire odometer assembly, with the exception of the tie rod, 5 may be put together with great facility, and introduced between the frame members 16 and 17, and the tie rod may then be put in place, thus securing all the parts firmly in proper position. The body of the drum is 10 made originally of such diameter as to spring out against the outer wall of the slot 9, so that its effective diameter is accurately determined. The flange 10 assists in engaging the body with the slot, since it acts as a pilot 15 against which the sheet metal may be pressed in contracting it to the diameter of the slot prior to its introduction.

The invention claimed is:

1. In an odometer provided with number 20 rings and internal transfer pinions, a drum, on which the rings revolve, comprising a cylindrical, longitudinally slotted sheet-metal body, two heads engaging the ends of said body and each provided with a circularly 25 curved slot corresponding in diameter and extent with, and receiving, the corresponding end of the body so as to confine the latter in all directions against lateral movement or distortion, and means for drawing the heads 30 tightly against the body.

2. In an odometer of the type comprising number rings, internal transfer pinions, and a drum upon which the rings revolve, the combination, with two frame members having 35 aligning perforations, of a tie-rod threaded into one of said perforations and having an enlarged head loosely engaging the other perforation, and the drum mounted upon the tie-rod and between the frame members, the 40 drum comprising a longitudinally slotted sheet-metal body, and two heads perforated to receive the tie-rod loosely, one head resting against that frame member into which the tie-rod is threaded, and the other head 45 being engaged by the head of the tie-rod so that the drum members may be clamped together by screwing the tie-rod into the threaded perforation.

3. The combination set forth in claim 2, in 50 combination, further, with a drive member rotatably mounted on the head of the tie-rod between the adjacent drum head and frame member and operatively connected in driving relation with the adjacent number ring 55 on the drum.

4. The invention defined by claim 1, said 60 last-named means comprising a tie rod coaxial with and within said body and extending beyond one of said heads whereby a drive gear 65 may be rotatably assembled on said tie rod extension for driving the adjacent number ring.

5. The invention defined by claim 1, said 70 last-named means comprising a tie rod coaxial with and within said body, said tie

rod extending at one end beyond one of said heads, the invention also including in combination a drive gear rotatable upon said tie rod extension, the drive gear operably connected to an adjacent number ring on the 75 drum.
